UNITED STATES PATENT OFFICE.

ROBERT BEARDSLEY, OF CHICAGO, ILLINOIS.

DESIGN FOR A LAMP SHADE OR SIMILAR ARTICLE.

Application filed October 19, 1927. Serial No. 23,791. Term of patent 3½ years.

To all whom it may concern:

Be it known that I, ROBERT BEARDSLEY, a citizen of the United States, residing at Chicago, in the county of Cook and State of Illinois, have invented a new, original, and ornamental Design for a Lamp Shade or Similar Article, of which the following is a specification, reference being had to the accompanying drawing, forming a part thereof.

Fig. 1 is a perspective view of a lamp shade, showing my new design; and
Fig. 2 is a bottom plan view of the lamp shade.

I claim:
The ornamental design for a lamp shade or similar article, as shown.

ROBERT BEARDSLEY.
